[57] CLAIM

The ornamental design for a shoe sole, as shown and described.

DESCRIPTION

FIG. 1 is a left side elevational view of a shoe sole showing our new design;

FIG. 2 is a right side elevational view thereof;

FIG. 3 is a bottom plan view thereof;

FIG. 4 is a front elevational view thereof; and

FIG. 5 is a rear elevational view thereof.

The broken line showing of a shoe upper in FIGS. 1-5 and the area within are environmental only and form no part of the claimed design.

FIG. 1.***FIG. 2.******FIG. 3.******FIG. 4.******FIG. 5.***
